ATTORNEY

UNITED STATES PATENT OFFICE

159,932

SLIP OR SIMILAR ARTICLE

Irving M. Schuyler, New York, N. Y.

Application January 18, 1950, Serial No. 7,315

Term of patent 14 years

(Cl. D3—26)

To all whom it may concern:

Be it known that I, Irving M. Schuyler, a citizen of the United States of America, residing in New York city, county of New York, and State of New York, have invented a new, original, and ornamental Design for a Slip or Similar Article, of which the following is a specification, reference being had to the accompanying drawing, forming part thereof, wherein,

I claim:

The ornamental design for a slip or similar article, substantially as shown.

IRVING M. SCHUYLER.
